BAG ASSEMBLY

Clarence W. Vogt, Norwalk, Conn.

Application July 13, 1948, Serial No. 38,477

9 Claims. (Cl. 229—53)

1

This invention relates to bags for the storage, protection, shipment and/or sale of various materials, and has for its main object a bag construction and assembly which facilitate the supporting, opening, filling, closing and sealing of the bags as they are advanced in succession to and past successive stations.

As an important feature of the invention the bags are connected together in series by one or more flexible strips of paper or other suitable material, and which strips may be employed to effect the advancement and/or opening of the bags and/or to assist in holding the bags open for filling. They also aid in the closing and sealing of the bags.

The invention is particularly applicable to bags formed of or lined with non-porous, heat-sealable material, whereby the bags when filled and closed may be hermetically sealed by the application of heat and pressure. In certain embodiments of the invention there are included pairs of bags which are connected together at or adjacent to their open ends, as disclosed and claimed in my application Serial No. 30,647, filed June 2, 1948, now Patent No. 2,628,013, of which this application is a continuation-in-part. Such pairs of bags may be supported by the connecting part during filling, closing and sealing, as disclosed in my application Serial No. 35,405, filed June 26, 1948, of which this application is also a continuation-in-part. The invention is also applicable to bags which are connected together in series or as a chain, but not in transverse pairs.

In its preferred form, and as an important feature of my invention, the strip which connects the bags in pairs at or adjacent to their open ends, also serves to connect the pairs of bags together in series or as a chain. This strip may be folded as an inverted V along a center line, so that the strip may rest on, be guided by, and moved along a horizontal support with the bags of each pair on opposite sides thereof.

As a further feature of my invention, and to facilitate the opening of the bags, two separate connecting strips are employed, each being attached to the outer wall of one bag of each pair at or adjacent to the open end. These connecting strips may be employed not only to pull or aid in pulling or feeding the bags along to successive stations for filling, closing, sealing, etc., but their main purpose is to pull the bag mouths open before said bags reach the filling station.

When such pairs of bag-opening strips are used, the bag mouths of each pair need not be

2

connected by an inverted V-shaped strip as above described, but the two bags of each pair may be connected in any other suitable manner at or near their open ends, so that they may be suspended on a supporting bar, or held upright, or otherwise supported during filling, closing and sealing. For instance, the connecting means between the two bags of each pair may be a spot seal between the bag walls, and of a character which will permit the later separation of the two bags of the pair.

The connecting strip or strips between one bag and the next successive one may be permanently glued or otherwise secured to the bag walls, and may be cut or torn in two between successive bags after filling, closing and sealing; but preferably the strips are secured to the bag walls by heat activated adhesive material, whereby after the strips have served their purpose the temperature at the sealing area may be raised to the required degree to soften the adhesive and thereby free the individual filled and sealed bags from the strips, or permit the strips to be pulled off. If desired, such removed strips may be reused for connecting together another series of bags, or used for sealing bag mouths after filling.

In the accompanying drawings I have illustrated somewhat diagrammatically various different embodiments of my invention. In these drawings:

Fig. 1 is a perspective view showing a plurality of pairs of connected bags, one pair of bags being in filling position and another pair shown as closed after being filled.

Fig. 2 is a section of a form somewhat similar to that shown in Fig. 1, but in which only one row of bags is connected in series.

Figs. 3, 4 and 5 are perspective views of other forms.

Fig. 6 is a section through a further form, in which the bags lie endwise of the chain instead of crosswise; and

Fig. 7 is a somewhat diagrammatic top plan view indicating how bag opening is automatically effected.

In the construction shown in Fig. 1 there are provided a plurality of pairs of bags A and B, which may be sections of tubing of thermoplastic material, and with the upper ends of the two bags A and B of each pair secured to opposite sides of a strip C which is bent along a center line extending lengthwise thereof, and to inverted V shape or U shape. Thus the bag pairs may be suspended or supported by placing this

strip on a horizontal bar or other support 10 along which the bags may slide. This support 10 may be a traveling metal band which moves endwise to advance the pairs of bags from one position to another.

In carrying out the present invention the V-shaped strip C which connects together the two bags of each pair is a long strip and connects the bag pairs in series to form a chain of bag pairs. Only three pairs of bags of such a chain are shown as connected to the strip C, but in commercial practice there might be a very large number of such bag pairs connected in series.

As a further important feature of my present invention the bags are also connected together in series by strips D substantially parallel to the strip C. The strips D are attached to the outer walls of the bags, and opposite to the walls which are attached to the strip C, and are disposed at or adjacent to the upper open ends of the bags. The bottoms of the bags may be free from each other, but are preferably connected in series. In the form shown in Fig. 1 the bag bodies have been formed of tubing, and a bottom strip folded to U-shape and adhesively secured to the bag bottoms to close and seal the latter and to connect them in series. As pointed out in my prior application Serial No. 30,647, filed June 2, 1948, now Patent No. 2,628,013, the bag bodies may be made of polyvinylidene chloride (Saran), and the strips may be made of paper coated with an adhesive which becomes tacky below the temperature at which the Saran will autogenously weld or seal.

In using the bag assembly shown in Fig. 1, the series of bag pairs are supported on the bar or other stationary or movable member 10, and are fed along in any suitable manner, preferably step by step in respect to the filling means. As shown, such filling means includes a pair of spouts or nozzles 11 which may lead from any suitable source of supply, with the usual control valves, measuring devices, etc. Such nozzles may have conical shaped ends or flanges or fins to facilitate the spreading open of the bag mouths. If desired, the nozzles may move downwardly into the bags before filling, and then up out of them to permit the next successive pair of bags to be brought to filling position.

In starting the operation, the pair of bags below the nozzles may be pulled open by hand, or in any other suitable manner. As the charge of liquid, powder, or material in other form is delivered into the pair of bags which are in filling position, such charge will further open up the bags. As the filling is taking place, the contents of the bags acts to further open up the bags, and as the outer walls of these bags are connected to the outer walls of the next successive pair of bags, this spreading apart of the outer walls of the pair being filled will act through the strips D to open up the lower ends of the next pair of bags. Thus, when a filled pair of bags is moved from beneath the nozzles, the next pair of bags will be brought beneath them and will have been automatically opened by the spreading apart of the strips D. Thus, the strips D serve as bag openers as well as bag advancing means, and they strengthen and reinforce the bag bottoms during and after filling, and insure against tearing of these seals and make the bags leak-proof and sift-proof. From Fig. 7 it will be seen how the filling of one pair of bags acts to open up the next successive pair.

Beyond the filling nozzles there may be provided a pair of rollers 12 which engage the outer

surfaces of the strips D and press them toward each other and thus close the bags. The rollers may be heated, so that in closing the bags the heat is transmitted through the strips D and hermetically seals the bags, if the walls of the latter be of thermoplastic material. The rollers 12 may be merely bag closers and sealers, and freely rotatable, in which case the strips may be pulled along solely by other rollers or by other pulling means beyond the rollers 12. If the rollers 12 be merely for closing and sealing, they may be replaced by non-rotatable heaters such as heated plates or shoes resiliently pressed toward each other and against the upper ends of the bags, to close and seal them.

The strips D may be connected to the bag walls by heat activated adhesive, so that when heat is applied to seal the bag mouths this heat will soften the adhesive on the strips D and permit the strips to be pulled off from the bags, or permit the filled bags to slip down and away from said strips. When heat activated adhesive is used on the strips D, the strips E need not connect the bottoms of the bags, or if they do, cutting means may be provided for serving such strips between successive bags.

Although it is preferable that the bags be connected in pairs, it is not essential to my invention in its broader aspect. In Fig. 2 I have shown how a single row of bags B' may be connected to strips D and C', provided the last mentioned strips be of sufficiently stiff material so that the fold will not open up by the weight of the bag and its contents; or if the bag be supported primarily by a horizontal wall or shelf 13 along which the bags may slide, or supported by a conveyor for supporting and carrying along the filled bags. In this figure I have shown the bottom of a bag closed by folding over the bottom end, as is common in bag constructions. Thus the connecting strip E shown in Fig. 1 need not be employed.

In the bag constructions above referred to, a strip C is employed which acts to support the bags. This is not essential in the broader aspects of my invention. As shown in Fig. 3, the two bags A² and B² of each pair are connected together adjacent to their upper ends by a spot or small area F, preferably of self-sticking or latex type of adhesive. The two bags of each pair will rest upon opposite sides of a horizontal support such as the bar 10, and the pairs of bags are connected together in series by strips D. These strips may be attached to the outer walls of the bags adjacent to the open end by heat activated or self-sticking adhesive, and preferably in small areas G. In this form the bags are shown as made of thermoplastic material and the lower ends or bottoms closed by heat sealing along a narrow area H. It is not necessary that one pair of bags be connected to the other, other than by the strips D, but if desired, they may be connected adjacent to their lower ends by short strips K secured in place by adhesive, and readily removable.

The bags as shown in Fig. 3 may be closed and heat sealed after filling, in the same way as described in connection with Fig. 1, and the filling of one pair of bags will act to open up the next succeeding pair by reason of the connecting strips D.

In Fig. 4 I have shown a construction quite similar to that in Fig. 1, except that the bags are of the gusset type, in which opposite walls are infolded. In this form I have shown the bags B³ as secured to the strip C at a substantial dis-

tance below the fold line, instead of at the fold line, as in Fig. 1. Bags of this character may be fed along to successive stations by pulling on the strip C instead of on side strips such as D, shown in Fig. 1, and the closing and sealing of the bags after filling may be effected by applying heat and pressure directly to the outer walls of the bags to press them against the strip C. Bag pairs may be filled and sealed before or after severance from the chain.

In Figs. 1, 2 and 3, the strips D are employed for pulling the bag mouths open. In some constructions other means may be employed for opening the bags. In Fig. 5 I have shown bags similar in all respects to those shown in Fig. 4, except that comparatively stiff labels L are secured to the outer walls of the bag and extend to some distance above the open ends of the bags. In feeding the bags along, the upper edges of these labels may engage guides which will push the bag mouths open before they reach the filling nozzles. The bags when filled may be removed from the supporting strip C by applying heat to loosen the heat-activated adhesive, and the labels L may, if desired, be folded over the closed upper ends of the bags, although when the bags are formed of thermoplastic material they may be readily closed and sealed by applying heat and pressure to the outer surfaces of these labels.

In the various constructions hereinbefore described, the bag pairs are connected together in series, with the upper ends of each row of bags substantially in alignment. The bag pairs or single bags may be connected in endwise rather than edgewise alignment. In Fig. 6 I have shown pairs of bags A⁴ and B⁴ connected together in pairs, and the successive pairs spaced apart endwise rather than edgewise. The two bags of each pair are preferably connected together by a spot seal near their open ends, and the bags can later be separated by peeling, the same as in Fig. 3, but the connecting strips D⁴ extend lengthwise of the bags rather than transversely thereof.

The connecting strips D⁴ may each be supported by pairs of rollers 14, the lower one of which may be heated. The rollers may be intermittently or continuously rotated to lift successive pairs of bags to the desired elevation where the pairs of bags may be automatically pulled loose from the strips, deposited on a support such as the bar 16, filled and sealed.

The bags A⁴ and B⁴ need not be connected in pairs, as the bags may be in a single row on one strip D⁴, and they may have closure flaps. Thus, as each bag is raised to the proper point it may be filled, the flap closed, and the bag liberated from the strip by the pulling of the latter between the rollers, so that the filled and closed bags may fall into a receptacle or onto a conveyor.

Where two longitudinal tapes are used, they are preferably laterally offset, so that in rolling the chain of bags the strips are not superposed, and a firmer roll may be formed. The strip or strips may serve its or their main purpose during the making of the bags to facilitate taking them from the bag machine, or to facilitate packing or rolling of a chain of the bags for shipment. The strip may be removed before the bags are filled.

Various other forms may be employed, in which bags or bag pairs are fed along by means of one or more strips or tapes adhesively secured thereto, and to filling, closing and sealing stations.

In Figs. 1 and 3 I have shown the strips D pro-

vided with perforations 15. These may serve to receive prongs or teeth of a feed means for pulling the tapes and chains of bags along during or between filling, closing, and sealing operations, and if the tape sections are to be left on the bags, said holes provide weak points at which the tapes or strips may be broken, cut, or easily torn in two.

Having thus described my invention, what I claim as new and desire to secure by Letters Patent is:

1. As an article of manufacture, a strip of sheet material adapted to be bent along a line extending lengthwise thereof to form an inverted V, and a plurality of pairs of bags having portions at their open ends connected to said strip along the length thereof, the two bags of each pair being on opposite sides of said line.
2. As an article of manufacture, a strip of sheet material adapted to be bent along a line extending lengthwise thereof to form an inverted V, and a plurality of bags having portions at their open ends connected to said strip along the length thereof and arranged in pairs, the two bags of each pair being in juxtaposed positions on opposite sides of said line, whereby upon supporting said strip substantially horizontally, said bags will be suspended from said strip with their open ends uppermost for filling.
3. As an article of manufacture, a strip of sheet material adapted to be bent along a line extending lengthwise thereof to form an inverted V, a plurality of bags having their open ends connected to said strip along the length thereof, and means independent of said strip for connecting each bag to an adjacent one.
4. As an article of manufacture, a strip of sheet material adapted to be bent along a line extending lengthwise thereof to form an inverted V, a plurality of bags having their open ends connected to said strip along the length thereof and arranged in pairs, the two bags of each pair being on opposite sides of said line, and means independent of said strip for connecting one bag of each pair to the adjacent bag of another pair.
5. As an article of manufacture, a strip of sheet material adapted to be bent along a line extending lengthwise thereof to form an inverted V, a plurality of bags of thermoplastic material each having one side wall at its open end connected to said strip, and a separate strip connected to each bag adjacent to the open end on the side wall opposite to that connected to the first mentioned strip.
6. As an article of manufacture, a strip of sheet material adapted to be bent along a line extending lengthwise thereof to form an inverted V, a plurality of bags of thermoplastic material each having one side wall at its open end connected to said strip, the bags being arranged in pairs along the length of said strip, and the two bags of each pair being on opposite sides of said line, and a pair of separate strips each connecting together in series one bag of each pair.
7. An article, according to claim 1, wherein the bags are connected to the strip with their top edges below the top of the strip to provide flap material for the bags.
8. An article, according to claim 1, wherein the outer sides of the bags of each pair are provided with relatively stiff material secured thereto and extending above the top edges of the bags.
9. As an article of manufacture, a plurality of pairs of bags, each pair of bags having inner

opposed side walls, outer side walls and open ends, means detachably connecting the inner opposed side walls of each pair of bags together and holding the inner side walls thereof in face to face relation with the open ends of the bags facing in the same direction, the connecting means being located adjacent to said open ends of the pair of bags, and strips of flexible material detachably connecting the outer side walls of the bags of different pairs together in a series and joining the pairs into a chain of pairs of bags in which the open ends of all of the bags face in the same direction, said strips being connected to said outer side walls of said pairs of bags adjacent to the open ends of said bags, said strips serving to advance said chain of bags to present the pairs of bags successively to a filling position

and to open said bags by movement of said strips away from each other.

CLARENCE W. VOGT.
